COMBINATION LOCK

Albert Sanowskis, Chicago, Ill.

Application July 26, 1940, Serial No. 347,573

10 Claims. (Cl. 70—305)

The invention relates to combination locks.

The objects of the invention are to provide an improved combination lock; which is adapted for manual and selective operation by a dial or equivalent means and which is simple in construction; which will automatically unlock the locking-bolt when the correct combination has been used to shift the tumblers into releasing position; which comprises an escapement device for controlling the successive movements of the tumbler-shifting member to successively shift the tumblers into releasing position; which comprises simple and improved setting mechanism for the tumblers; which is operable from the outside of the door only by use of the correct combination and which can be locked and released from the inside of the door without the combination; and others which will appear from the detailed description.

The invention consists in the several novel features which are hereinafter set forth and which are more particularly defined by claims at the conclusion hereof.

In the drawings: Fig. 1 is a horizontal section of a lock embodying the invention applied to a door, the bolt being shown in its locking position. Fig. 2 is a horizontal section taken on line 2—2 of Fig. 1. Fig. 3 is a vertical section taken on line 3—3 of Fig. 1. Fig. 4 is a perspective of the escapement-device for controlling the tumbler-shifting member for successively engaging and shifting the tumblers; Fig. 5 is a perspective of the sleeve which is rotatable with the manually and selectively operable dial to impart movement to the tumbler-shifting member; Fig. 6 is a detail perspective of the support for the frame for shifting the tumbler-shifting member. Fig. 7 is a side elevation of the dial for manually and selectively operating the tumblers. Fig. 8 is a vertical section similar to Fig. 1, illustrating the tumblers and locking-bolt in the positions assumed when the door is unlocked. Fig. 9 is a section taken on line 9 of Fig. 8, illustrating the controlling device for the locking-bolt in position assumed when the bolt is retracted; Fig. 10 is a view similar to Fig. 9 illustrating the controlling device in position to lock the bolt. Fig. 11 is a section taken on line 11—11 of Fig. 8. Fig. 12 is a perspective of a portion of the escapement device for controlling the step-by-step movements of the tumbler-shifting member.

The invention is exemplified as used for locking a door 20. A case 21 is secured in a cavity in the door. A slidable bolt 22 is mounted in said case

and adapted to enter a socket-plate 23 in the door-jamb to lock the door.

The lock is adapted to be operated to unlock bolt 22 by a manually and selectively operable dial 24 which is rotatably mounted at the outer side of the casing 21 and is adapted by successive strokes to shift tumblers predetermined distances corresponding to the indications on the dial. Dial 24 is provided with pockets 25 to receive a finger 10 for the rotation of the dial through predetermined arcs of different magnitude and until the finger is arrested by a fixed stop 26. A cylindrical sleeve 27 is secured to rotate with, and extends inwardly from, the dial. A convolute spring 28 around sleeve 27 has one of its ends secured to a bracket 29 which is fixed to case 21 and its other end secured, as at 30, to sleeve 27, for retracting the dial after each operative stroke in one direction and when it is released by the operator. The dial 20 is normally positioned by a stop 31 on the dial and which is held against a fixed stop 29 by spring 28.

A series of tumblers 32 are coaxially pivotally mounted on a shaft 33. Shaft 33 is fixed in brackets 34 and is provided with spacing sleeves 35 between the tumblers so that each tumbler will be independently and individually movable on said shaft. Sleeve 27 is rotatable around a cylindrical support 40 (Fig. 6) which is fixedly 25 secured to the inner face of one side of case 21.

The mechanism for shifting the tumblers responsive to the rotative strokes of the dial 24 and sleeve 27 in one direction, comprises a frame 36 (Fig. 4) which is slidably in support 40. Frame 35 has end-walls 37 which are provided with lugs 38 which are slidably confined in slots 39 formed in support 40. Sleeve 27 (Fig. 5) rotates with the dial and fits around the cylindrical upper portion of support 40, and is provided with helical 30 slots 41. Studs 42 project outwardly from lugs 38 on frame 36 and into the slots 41 in sleeve 27. Oscillatory movements of the sleeve 27 from the dial will impart reciprocating strokes to studs 42 and frame 36 to operate the tumblers according 45 to the magnitude of the dial strokes. A crossbar 43 has its ends fixed in the end-walls 37 of, and is reciprocated with, frame 36 (Fig. 4). A tumbler-shifting member 44 is slidably mounted on bar 43 for step-by-step movements into positions for successively and individually shifting the tumblers. Member 44 is non-rotatable on bar 43 and is provided with an integral arm 45 for engaging a tumbler during each reciprocation of frame 36 by an operating stroke of the dial. Each tumbler 50 comprises an arm 32' which is adapted to be engaged

by the inward movement of arm 45 of member 44. Each tumbler is provided with a notch 32^a. The notches in the series of tumblers are relatively located so that a predetermined combination of strokes must be imparted to the tumblers, respectively, by the dial 24 to bring all of the notches into alignment for the release of the bolt 22 to unlock the door, as hereinafter described.

An escapement-device is provided to successively position arm 45 for singly shifting the tumblers into position for the release of bolt 22. A coil-spring 47 around bar 43 and between member 44 and one end 37 of frame 36 shifts member 44 and arm 45, under control of an escapement-bar 50, into positions for successive operation of the tumblers. A resilient strip or dog 48 which fits against a lug 49 which is integral with member 44 engages escapement-bar 50, to control the step-by-step movements of member 44 and arm 45 and permits retraction of arm 45. Escapement-bar 50 is slidably relatively to member 44 in slots 51 formed in the end-walls 37 of frame 36 and is normally pressed against the inner end of said slots by a leaf-spring 52. Bar 50 is provided with a serrated slot 53 into which the end of resilient dog 48 normally extends. This slot is provided with serially connected inclined portions and portions parallel to the plane of movements of member 44 which are formed by teeth 54 on one end of the slot having straight edges 54' and teeth 55 on the opposite side having upwardly inclined edges 55'. When frame 36 is in its normal position the resilient dog 48 engages the edge 54' of the left-hand (Fig. 4) tooth 54 and arrests the movement of member 44 and arm 45. The dog 48 then abuts against lug 49 on member 44 so it prevents movement of said member by spring 41. A spring 56 is provided to impart relative movement between escapement-bar 50 and frame 36 during the initial portion of each instroke of frame 36. This spring 56 is ineffective while the frame 36 is in its normal position so that leaf-spring 52 will then hold bar 50 in its inner position in frame 36. During the commencement of an instroke of frame 36, spring 56 will engage a lug 57 on escapement-bar 50 and hold the bar against inward movement with frame 36. The force of spring 56 preponderates that of spring 52. During this retardance of bar 50 and its movement relatively to frame 36, resilient dog 48 will be forced by spring 47 below the edge 54' of the first tooth 54 and in the escapement-slot and member 44 will be pressed to the right (Fig. 4) until dog 48 engages the inclined edge 55' of the first tooth 55 in the escapement-bar. Arm 45 will then be aligned with the first tumbler 32 of the series so that that tumbler, by the instroke of frame 36, will be shifted in accordance with the extent of rotation of the dial. After the escapement-bar 50 reaches the upper ends of slot 51 it will continue to move inwardly with frame 36 so the engaging relation of dog 48 and bar 50 will be maintained throughout the remainder of said stroke. When the dial 24 is retracted by spring 28, sleeve 27 shifts frame 36 outwardly. Before frame 36 reaches its normal position, the spring 56 becomes ineffective and leaf-spring 52 will move the escapement-bar 50 inwardly in frame 36. Dog 48 will ride over the end of inclined edge 55' of the first tooth 55 with which it has been engaged until it is arrested by the edge 54' of the second tooth 54 from the force applied to member 44 by spring 47. Each succeeding reciprocation of frame 36 responsive to a movement of the

dial will result in shifting member 44 and arm 45 through the succeeding branches of the slot 53 in escapement-bar 50 until all of the tumblers have been operated. In order to permit the shifter-member 44 and arm 45 to be re-set into normal position after each series of four operations, dog 48 is resilient and free to flex so it will ride over the teeth of the escapement-bar, when said member is manually retracted against the force of spring 47.

The arcuate edges of the tumblers 32 are adapted to control the release of the locking-bolt 22, as hereinafter described. Each tumbler is provided with a notch 32^a. Normally the notches 15 in the tumblers are positioned so that they will prevent the bolt 22 from being retracted and so that each of the tumblers must be shifted through a predetermined arc according to the predetermined combination in order to bring the notches 20 into alignment for the release of the bolt 22. When the bolt 22 is in its releasing position the notches 32^a of the tumblers are in alignment. When it is desired to set the tumblers into locking position it is necessary to retract the tumbler-shifting member 44 to its normal position 25 for operating the first tumbler of the series and to shift the tumblers into locking position. The device for restoring the tumblers to their locking position and retracting member 44 comprises a push-button 60 which is provided with a stem 30 which is slidably mounted in the cross-wall of support 40. An inclined cam 61 on the inner portion of the stem of said button is adapted to engage an incline 62 on the tumbler-shifting member 44. When button 60 is depressed, cam 61 will force member 44 to the left against the force of spring 47 and resilient dog 48 will ride over the teeth surrounding slot 53 of the escapement-bar 50 until it passes into the left-hand end of the slot. When the button 60 has been moved inwardly, dog 48 will be arrested against movement to the right by the straight edge 54' of the first tooth 54 so that the member 44 will be set in position for a series of four operations to successively operate the tumblers.

The stem of button 60 is also provided with an extension 64 for re-setting the tumblers 32 from their bolt-releasing position to their locking position. Extension 64 is adapted to rock an arm 50 65 when button 60 is depressed. Arm 65 is fixed to a rock-shaft 66 which is journaled in bearings 67 and said shaft has affixed thereto a pair of parallel arms 71, the distal ends of which are cross-connected by a bar 68. When button 60 55 is depressed, extension 64 will rock shaft 66 and arms 71, so that bar 68 will engage the extensions 32' of the tumblers and shift them to their locking position.

A spring 74 is connected to locking-bolt 22 to 60 retract the bolt against a stop 74' when the bolt is released. Shaft 66 is provided with an arm 75 which is adapted to engage the inner end of bolt 22 and to slide it outwardly into socket 23 when the setting button 60 is depressed, simultaneously with the setting of the tumblers in their locking position and the retraction of the tumbler operating member 44.

The retraction of bolt 22 by spring 74 is controlled by a locking-member 70 which comprises 70 a pair of arms 71, the free ends of which are rigidly cross-connected by a bar 72. Arms 71 are coaxially pivoted at 73 to the sides of the locking-bolt 22. Bar 72 is adapted to enter the notches 32^a in the tumblers when the notches 75 of all of the tumblers are aligned and in reg-

istry with said bar, to release the locking-bolt 22. Bar 72 is held against the arcuate edges of the tumblers when the notches 32^a do not all register with said bar, and when thus engaged member 70 will cause the bolt 22 to be held in its locking position. When member 70 and bar 72 are in locking position and bolt 22 is in its locking position, the force of spring 74 will be applied to hold cross-bar 72 in engagement with the edges of the tumbler by a latch 76 which is pivoted at 77^a to the inner face of bolt 22. This latch is provided with a shoulder 78 which engages one of the arms 71 when the locking-member 70 is in its locking position to hold bar 72 against the edges of the tumblers 32, as illustrated in Figs. 1 and 10, and with a notch 79 which is adapted to release said arm for pivotal movement so that bar 72 can pass into notches 32^a. Bar 72 is held against the tumblers by the force of spring 74 applied through bolt 22 and arm 71 and latch 76 and when the notches 32^a in the tumblers 32 have been shifted into registry with said bar as the result of the correct predetermined strokes of the dial 24, bar 72 will pass into notches 32^a. This will permit a sufficient inward movement of the bolt 22 to cause an abutment 80 on latch 76 to engage a cam 81 which is fixedly secured to the case. This engagement will swing latch 76 against the force of spring 82 sufficiently to bring notch 79 in registry with arm 71 so that the spring 74 can fully retract the bolt 22. As a result, when the tumblers have been correctly shifted to bring their notches 32^a into registry with bar 72 of locking-member 70, spring 74 will automatically retract bolt 22. A light spring 83 is applied to one end of latch 76 to hold it against a stop 83' while the bolt 22 is being shifted into its locked position by arm 75.

A lever 96 pivoted on shaft 33, is operable by tumbler-resetting bar 68, and is provided with a cam-edge 97 for engaging the bar 72 of the locking-member 70 to withdraw said bar from the notches 32^a in the tumblers 32 so that when the button 60 is operated to shift the tumblers into locking position, bar 72 will release the tumblers for pivotal movement in advance of the engagement of bar 72 with the tumblers. A spring 98' is applied to lever 96 to retract said lever, bar 68, arms 77, shaft 66, and arm 75, after bolt 22 and the tumblers have been shifted into locking position.

A device is provided for unlocking the door from the inner side thereof without operation of the dial 24 and for locking the door from the inside without operating button 60. This device comprises a push-button 99 which is slidably mounted in a socket in the inner side of case 21 and normally pressed outwardly by a spring 91 and arrested by a stop 92. Button 99 is provided with a stem 93 which is adapted to engage an inclined cam-surface 94 in a slot in bolt 22. A bar 95 is fixedly secured to stem 93. When button 99 is pressed inwardly, stem 93 will slide bolt 22 into socket 23 against the force of spring 74. An extension 96^a on bar 95 is adapted to engage re-setting bar 68 to rock lever 96 and move bar 72 of locking-member 70 out of the notches 32^a in the tumblers 32 and also to operate bar 68 to set the tumblers in their normal locking position.

Button 99 is also adapted to release bolt 22 from its locking position for retraction by spring 74. A one-way spring-pressed dog 98 is pivoted to stem 95 to engage the inner end 76^a of latch 76

76 during the in-stroke of button 99 and to shift latch 76 from its locking position when the bolt 22 is in socket 23, as shown in Fig. 10, to bring notch 79 in latch 76 into registry with arm 71 of locking-member 70 so that the bolt 22 will be free to be retracted by spring 74. The operation of the locking-mechanism will be as follows: assuming the bolt 22 to be in its released position, as shown in Figs. 8 and 9, and the bolt is to be shifted into its locking position from the outer side of the door, button 60 will be pressed inwardly. Extension 64 on the stem of said button will rock arm 65, and shaft 66 and shift setting-bar 68 to first swing lever 96 to withdraw bar 72 of locking-member 70 out of the notches 32^a in the tumbler, and then shift the tumblers to their locking position. Simultaneously arm 75 will slide bolt 22 into socket 23. The pivot 73 of arm 71 will be shifted so said arm will swing sufficiently to permit shoulder 78 of latch 76 to be pressed by spring 82 into engagement with arm 71 so that said shoulder 78 will lock member 70 against pivotal movement away from the tumblers. The bolt 22 will then be locked in its locking position by the tumblers and member 70. Simultaneously, cam 61 on the stem of button 60 will engage shifting-member 44 on rod 43 and shift said member against the force of spring 47 to its normal position at the left-hand side of the escapement-bar 50. The resilient dog 48 will slide over the teeth of the locking-bar. When it is desired to shift bolt 22 into locking position from the inside of the door, button 99 will be pressed inwardly so its stem 93 acting on cam-surface 94 of bolt 22, will slide the bolt outwardly against the force of spring 74. Extension 96^a on the stem of button 99 will operate setting-bar 68 and lever 96 to first release bar 72 of the locking-member 70 from the tumblers and then shift the tumblers into locking position, as before described.

To open the door from the outside it is necessary to operate the dial once for each tumbler, according to the correct combination, and shift, through sleeve 27 and studs 42, frame 36 distances corresponding to the magnitude of the angular movement necessary to bring the notches 32 in the tumblers into registry with bar 72 of locking-member 70. During the initial portion of the instroke of frame 36 the escapement-bar 50 will be retarded in frame 36 by spring 56 to position member 44 for shifting the first tumbler of the series and during the continuation of the instroke member 44 will shift said tumbler. During the latter portion of the outstroke of frame 36 and the retraction of the dial by spring 28, escapement-bar 50 will be retarded against outward movement with frame 36 by spring 52 so that dog 48 will pass through the slot in the escapement-bar 50 into engagement with the straight side 54' of the second tooth. Each of the three succeeding strokes of the dial and frame 36 will similarly operate the escapement-device to successively position shifting-member 44 for one of the remainder of the tumblers. When the dial has been operated according to the correct combination for the four tumblers, all of the notches 32^a in the tumblers will be in registry with bar 72 of the locking-member 70. Thereupon, the locking-member 70 will be free to move inwardly a sufficient distance to disengage shoulder 78 of latch 76 from arm 71 of locking-member 70 and permit the bolt 22 to be retracted by spring 74.

To unlock the bolt 22 from the inside of the

door, button 90 will be pressed inwardly so that dog 93 on bar 95 on stem 93 will trip latch 76 during its stroke to disengage shoulder 78 from arm 71 of locking-member 70 and permit spring 74 to retract the bolt 22 into the position shown in Fig. 8.

While the invention has been illustrated and described with a series of four tumblers, it will be obvious that any desired number of tumblers may be provided to provide for a greater number of combinations.

The invention is not to be understood as restricted to the details set forth, since these may be modified within the scope of the appended claims, without departing from the spirit and scope of the invention.

Having thus described the invention, what I claim as new and desire to secure by Letters Patent, is:

1. A combination lock comprising a plurality of coaxially pivoted tumblers, a member for shifting the tumblers, manually operable means for imparting selective operative strokes to said member, and an escapement-device operable by said means and comprising a toothed bar and an element controlled by the teeth of said bar for producing step-by-step movements of the member for successive operation of the tumblers.

2. A combination lock comprising a plurality of coaxially pivoted tumblers, a member for shifting the tumblers, manually operable means for imparting selective operative strokes to said member, and an escapement-device operable by said means and for producing step-by-step movements of the member for successive operation of the tumblers, said escapement-device comprising a bar provided with teeth, an element on said member co-acting with said bar, and spring means for shifting said member relatively to the bar.

3. A combination lock comprising a plurality of coaxially pivoted tumblers, a member for shifting the tumblers, manually operable means for imparting selective operative strokes to said member, an escapement-device operable by said means and for producing step-by-step movements of the member for successive operation of the tumblers, said escapement device comprising a bar provided with teeth, and a resilient element on said member co-acting with said bar, and means for manually retracting said element across the bar.

4. A combination lock comprising a plurality of coaxially pivoted tumblers, a movably supported frame, manually operable means for imparting selective operative strokes to said frame, a member movable with said frame to shift the tumblers and movable in said frame for successively engaging the tumblers, and means for moving the member step-by-step in the frame for the successive operation of the tumblers.

5. A combination lock comprising a plurality of coaxially pivoted tumblers, a movably supported frame, manually operable means for imparting selective operative strokes to said frame,

5 a member movable with said frame to shift the tumblers and movable in said frame for successively engaging the tumblers, and means for moving the member step-by-step in the frame for the successive operation of the tumblers, comprising an escapement-bar and a dog on said member.

6. A combination lock comprising a plurality of coaxially pivoted tumblers, a movably supported frame, manually operable means for imparting selective operative strokes to said frame, 10 a member movable with said frame to shift the tumblers and movable in said frame for successively engaging the tumblers, means for moving the member step-by-step in the frame for the successive operation of the tumblers, comprising an escapement-bar slidably mounted in said frame and a dog on said member, and a spring for slidably shifting said member in said frame under control of the escapement-device.

7. A combination lock comprising a plurality 20 of coaxially pivoted tumblers, a slidably supported frame, manually operable means for imparting selective operative strokes to said frame, a member movable with said frame to shift the tumblers and slidably in said frame for successively engaging the tumblers, means for moving the member step-by-step in the frame for the successive operation of the tumblers, comprising an escapement-bar slidably mounted in said frame and a dog on said member, and a spring for slidably shifting the member in said frame under control of said device.

8. A combination lock comprising a plurality 30 of coaxially pivoted tumblers, a member for shifting the tumblers, manually operable means for imparting selective strokes to said member for shifting the tumblers, including a rotatable sleeve provided with helical means, means operable by said helical means for shifting said member, and means controlled by the movements of the sleeve for shifting the member step-by-step to successively operate the tumblers.

9. A combination lock comprising a plurality 40 of coaxially pivoted tumblers, a member for shifting the tumblers, manually operable means for imparting selective strokes to said member for shifting the tumblers, including a dial and a sleeve rotatable with the dial and provided with helical means, means operable by said helical means for shifting said member, and means controlled by the movement of the sleeve for shifting the member step-by-step to successively operate the tumblers.

10. A combination lock comprising a plurality 50 of coaxially pivoted tumblers, a member for shifting the tumblers, manually operable means for imparting selective strokes to said member for shifting the tumblers, including a rotatable sleeve provided with helical means, a slidable frame in which the member is slidably mounted, means operable by said helical means for shifting said frame, and means controlled by the sliding movements of the frame for shifting the member to successively operate the tumblers.

ALBERT SANOWSKIS.
